HENRY BUEHLER, OF NEW YORK, N. Y.

Letters Patent No. 65,640, dated June 11, 1867.

IMPROVED DIVAN AND BED.

The Schedule referred to in these Letters Patent and making part of the same.

TO ALL WHOM IT MAY CONCERN:

Be it known that I, HENRY BUEHLER, of the city, county, and State of New York, have invented a new and improved Combined Divan and Bed; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

The present invention consists in so constructing a divan that it can be opened or adjusted in its various parts so as to be used as a bed, or, in other words, brought to a suitable position for a person or persons to recline or lie upon the same with the same comfort and ease as upon any bed of the ordinary construction. In the accompanying plate of drawings my improved combined divan and bed is illustrated—

Figure 1 being an elevation or view of one end of the combined divan and bed, when folded or closed up and in shape for use as a divan; and

Figure 2, a central longitudinal vertical section, with the divan opened and adjusted by its several parts for use as a bed.

Similar letters of reference indicate like parts.

A, in the drawings, represents the seat portion of the divan, supported upon legs B, one at each corner. This seat portion A is made in two parts or sections marked respectively C and D in the drawings, that, upon the front side of the divan, are hinged together so as to be opened from and closed the one upon the other, the upper section C of the two being suitably constructed and upholstered for use as a seat, while the lower section D is made hollow or of a box shape for holding the mattress E, that when the divan is unfolded, as will be hereinafter described, is to be placed upon the same, as a cushion or bed for reclining or lying upon. This mattress E is made in sections, as shown in fig. 2 of the drawings, so that it can be folded up when not to be used, and placed in the box section of the seat portion, this section being provided with a detachable cover or lid, F, for a support to the mattress E. To the section C legs G are hung, to support its outer edge when opened. H, the back to the divan, suitably upholstered, and covered to correspond with the seat portion. This back H is hinged to the back edge of the lower section of the seat B, so that it can be let down into a horizontal position or nearly so, where, by means of adjustable legs I, it is to be supported; these legs being secured by hinges to the back. J, a bolt on back H, for fastening it in its upright position, and K set or thumb-screws for securing the back H and the upper section of the seat portion together, when the divan has been brought or adjusted for use as a divan.

From the above description of my improved divan, together with the figures of the accompanying plate of drawings, it is plain to be seen that it can be easily adjusted in position by its several parts for use as a bed, while when all closed up it presents all the outside appearance of the ordinary divan, whereby is produced a most desirable, useful, convenient, and compact article of furniture for small or contracted apartments.

Having thus described my invention, I claim as new, and desire to secure by Letters Patent—

A divan, constructed substantially in its seat and back portions so as to be used and adjusted substantially as described for the purposes specified.

The above specification of my invention signed by me this 9th day of March, 1867.

HENRY BUEHLER.
